Specification for Design.

Patented Jan. 25, 1921.

Application filed July 21, 1920. Serial No. 398,030. Term of patent 14 years.

To all whom it may concern:

Be it known that I, GARDNER C. KAVANAUGH, a citizen of the United States of America, and a resident of the city of Rochester, in the county of Monroe and State of New York, have invented a new, original, and ornamental Design for a Piano-Case, of which the following description, in connection with the accompanying drawing, is a specification.

The single figure of the drawings is a perspective view of a piano case showing my design.

I claim as my invention:

The ornamental design for a piano case, as shown.
